Primary Examiner — Ian Simmons*Assistant Examiner* — Carissa C Fitts(74) *Attorney, Agent, or Firm* — Womble Carlyle Sandridge & Rice, LLP(57) **CLAIM**

The ornamental design for a light, as shown and described.

DESCRIPTION

FIG. 1 is a perspective view of a light, in accordance with the present invention;

FIG. 2 is a front elevation view of the light of FIG. 1;

FIG. 3 is a rear elevation view of the light of FIG. 1;

FIG. 4 is a left elevation view of the light of FIG. 1;

FIG. 5 is a right elevation view of the light of FIG. 1;

FIG. 6 is a top plan view of the light of FIG. 1; and,

FIG. 7 is a bottom plan view of the light of FIG. 1.

The broken line showing represents portions of the article not claimed and forms no part of the claimed design.
